COLLAPSIBLE TUBELIKE CONTAINER

Monte C. Caliman, Jr., Livingston, N.J., assignor to Unette Corporation, Livingston, N.J., a corporation of Delaware

Filed Mar. 22, 1967, Ser. No. 6,332

Term of patent 14 years

(Cl. D9—194)

FIG. 1

I claim:

The ornamental design for a collapsible tubelike container, as shown.
